UNITED STATES PATENT OFFICE.

FREDERICK C. MILLER, OF CINCINNATI, OHIO.

REAR AXLE FOR AUTOMOBILES.

No. 922,308.

Specification of Letters Patent.

Patented May 18, 1909.

Application filed July 16, 1908. Serial No. 443,872.

To all whom it may concern:

Be it known that I, FREDERICK C. MILLER, a citizen of the United States, residing at Cincinnati, in the county of Hamilton and State of Ohio, have invented certain new and useful Improvements in Rear Axles for Automobiles, of which the following is a specification.

My invention relates to an improvement 10 in rear axle construction for automobiles employing shaft drive.

The object of the invention is to provide a one-piece axle of great strength and rigidity, having simple and convenient provision for 15 receiving and supporting the gear casing.

Another object of the invention is that this gear casing supporting section of the axle, being the intermediate portion thereof, shall be of superior rigidity, so as to constitute 20 an element of increased strength at this point, rather than of weakness.

Another object of the invention is that the gear case supporting section of the axle shall permit of the ready insertion and removal of 25 the case, so that standard axles and cases may be readily interchangeable in case of breakage of either of these elements.

The features of the invention are more 30 fully set forth in the description of the accompanying drawing, forming a part of this specification, in which:

Figure 1 is a side elevation, partly in section, of my rear axle. Fig. 2 is a section on line x, x , Fig. 1. Fig. 3 is a section on line 35 y, y , Fig. 1.

The axle is composed of a one-piece solid forging 1, having the intermediate section 2 arched above the plane of the ends of the piece, and constituting a solid gear case sup-

port. The ends or horizontal portions of the 40 axle are horizontally hollow to provide for the reception of the shaft ends. The ends of the axle are exteriorly turned to provide bearings 3 for the spring seats.

4 represents the gear casing of spherical 45 form, preferably, and consisting of the section 5 with a removable cap 6. The section 5 is provided with a flange 7 through which pass the bolts 8 for securing the casing to the solid arch 2. In this way, the gear case is 50 suspended from and protected by the arch, which is the solidest portion of the structure. This construction also provides for the greatest possible space between the road and the bottom of the casing. 55

9 represents the tubular front end of the casing for receiving the transmission shaft from the front of the vehicle.

Having described my invention, I claim:

1. A one-piece axle consisting of a solid 60 forging, having its ends longitudinally hollow, and having a solid intermediate arch, a gear casing provided with a flange bolted to the arch, whereby the casing is accessibly suspended from and supported by the solid 65 arch, substantially as described.

2. A one-piece axle consisting of a solid forging having its ends longitudinally hollow, and having a solid intermediate arch, and a gear casing secured within said arch, substantially as described. 70

In testimony whereof, I have hereunto set my hand.

FREDERICK C. MILLER.
